INVENTOR

UNITED STATES PATENT OFFICE.

ROSS M. G. PHILLIPS, OF NEW HAVEN, CONNECTICUT.

FLATIRON.

Application filed June 22, 1921. Serial No. 479,439.

To all whom it may concern:

Be it known that I, Ross M. G. PHILLIPS, a citizen of the United States, residing in the city and county of New Haven, State of Connecticut, have invented a new and useful Improvement in Flatirons, of which the following, when taken with the accompanying drawings, is a specification.

The objects of my invention are: to provide automatic means for shutting off the supply of fuel to an iron: to provide said automatic means readily reversible for right or left handed use: a further object of my invention is to provide an iron and a stand therefor for purposes of preheating.

Referring to the drawings, which show illustrative embodiments of my invention, Fig. 1 is a side view of my improvement.

Fig. 2 is a front view of the handle bow showing perforations to radiate heat.

Fig. 3 is a side view in section of the means of attaching the handle bow to the iron.

Fig. 4 is another side view without my improved means of attaching the handle bow to the iron.

Fig. 5 is a rear view showing the switch, operating link and spring. The position for left handed use being shown by the broken lines.

Fig. 6 is a front view of Fig. 1—the iron being shown as adapted for right handed use.

Fig. 7 is another front view of Fig. 1 with the thumb latch, switch and spring shown in heat operating position—that is the handle has been partly turned to overcome the tension of the spring and the switch is in lowered or closed position.

Fig. 8 is a plan view in cross section of the handle on the lines A—A of Fig. 1.

Fig. 9 is a vertical cross section of the switch used. The spring adapted to hold the circuit normally open is also shown.

Figs. 10 and 11 show the iron supported upon a stand for preheating purposes, the said stand operating with my automatic improvement to hold the switch in closed position. Fig. 10 is a view from the front end of the iron and stand. Fig. 11 is a side view of the iron and stand.

Fig. 12 is a front view showing the thumb rest adapted for left handed use: the thumb rest is shown in heating position. The dotted lines in Fig. 12 show the thumb rest in nonheating position for left handed use.

Figs. 13 and 14 illustrate another embodiment of my invention. Fig. 13 is a side view, the iron being shown mounted upon my improved stand. In this form of my invention the handle is movably mounted in the handle bow and the connecting means for switch operation is firmly attached to the handle.

Fig. 14 is a plan view in cross section of the handle construction used in the embodiment of my invention set out in Fig. 13.

Figs. 15 and 16 illustrate a form of stand to be used for preheating purposes with the construction shown in Fig. 13. In this construction the preheating latch is held in position by a cross bar.

Figs. 17, 18, 19, 20, 21, and 22 illustrate an embodiment of my invention in which a push button switch is used. In the embodiments illustrated, this switch is operated by a thumb latch operating a movable shaft in a fixed handle as is shown in my preferred form (Fig. 1).

Fig. 17 is a side view.

Fig. 18 is a top view of the handle.

Fig. 19 is a rear view showing the parts in circuit opening or nonheating position.

Fig. 20 is a rear view showing the parts adapted for left handed use.

Fig. 22 is a plan view of a cross section of the handle and spring.

The iron is of any standard construction with an electrical heating unit with connector posts 18 in plug socket 19. (Fig. 9). A bracket 2 is fastened to the iron 1.

For the purpose of avoiding the spread of heat from the iron to the handle, I employ the following means of attaching the handle bow to the iron:

A plate 51 is mounted on the iron 1 by the screws 52. Plate 51 is removed from iron 1 by contact points 53 which seat upon heat insulating pads 54 made of asbestos or other suitable heat insulating material.

Handlebow 2 is attached to plate 51 by screws 55 and is separated therefrom by contact points 56 which seat on heat insulating pads 57 on plate 51. Heat insulating washers 59 (Fig. 3) are used with screws 52 and 55.

The handlebow 2 is made with perforations 58 to radiate as much as possible any heat reaching the handlebow 2.

The handle 3 is mounted on handle bow 2 in a fixed position in my preferred form. (See Fig. 8.) It comprises an exterior of

wood or other suitable material mounted on the tubular handle bolt 4 as shown, and held in rigid position by nut 5.

In the tubular handle bolt 4 slides a movable shaft 6. Shaft 6 is separated from tubular bolt 4 by a bushing of heat insulating material 21. Shaft 6 has a cap 7 on which is mounted an arm 8 comprising a thumb latch. Also on cap 7 is mounted a preheating latch 9. This is preferably mounted on cap 7 opposite to thumb latch 8. Shaft 6 extends through the tubular bolt 4 and projects at the rear of the handle. On the rear end of shaft 6 is fixedly mounted arm 13 (Fig. 1) held in position by nut 6^a on shaft 6. Pivoted on arm 13 is an adjustable link 14. (Figs. 4 and 5.)

To an electrical connection plug switch 15^a is attached an electric cord 15^b which 20 may be connected to any convenient source of electric supply. Plug switch 15^a is adapted to engage connector posts 18 and has a quick make and break toggle switch 16 of ordinary construction operated by a toggle lever 15 (Fig. 9).

To the upper part of lever 15 is attached a tension spring 20 which is also attached to and holds switch lever 15 in the position shown in Fig. 9—that is so that the make 30 and break switch 16 is in a nonheating position.

Adjustable link 14 pivoted on arm 13 is connected to switch lever 15 (Fig. 1).

The parts—thumb latch 8, shaft 6, arm 35 13 and adjustable link 14 are aligned so that movement downwardly of thumb latch 8 causes lever 15 to overcome the tension of spring 20 and to close the circuit in make and break switch 16 in plug 15^a. When the 40 pressure on thumb latch 8 is removed lever 15 returns to its normal position (see Fig. 9) and the circuit in switch 16 is broken. (See Fig. 6.)

In Figs. 10 and 11 I have illustrated an 45 embodiment of my invention when used with a stand for preheating purposes.

The flat iron holder 24 is mounted on plate 25 which may be made of asbestos, with a base comprising a rod 27 bent to 50 form a suitable support. There is a wire frame support 29. Rod 27 has a projecting arm 28. The flat iron normally rests on support 24 for nonheating. When the flat iron is to be preheated for use it is placed on support 29 and preheating latch 9 is placed 55 on arm 28 after thumb latch 8 has been pressed down to the position shown in Fig. 7, i. e., in heating position. Preheating latch 9 has a notch 10 to prevent it sliding over arm 28.

My invention is further illustrated by the 60 embodiments illustrated in Figs. 13, 14, 15, 16, 17, 18 and 19.

In Figs. 13 and 14 there is illustrated a 65 form of my invention which omits the

thumb latch shown in my preferred form and operates by movement of the handle rather than by movement of a shaft within the handle as shown in my preferred form. (Fig. 1.)

The handle 3 (Fig. 14) is loosely mounted on handle bolt 35. To the front of handle 35 is attached preheating latch 9 and to the rear of handle 35 is attached an arm 13 and operates upon the other parts as in my preferred form.

In Figs. 17, 18, 19, 20, 21, and 22 the fixed handle and movable shaft therein is used as in my preferred form (Fig. 1) but different means are used to connect and operate the 80 shaft 6 and switch 16. The shaft 6 has attached to it a cam 60 (Fig. 19) which is rotated by shaft 6 on the rear end of the handle 3. Mounted on handle 3 is a spring yoke 43 extending over push button switch 42 in plug 15^a which is of any ordinary design having push buttons 61 and 62. Spring yoke 43 has stops 63 on the inside thereof and is normally pressing on push button 61, i. e., the "off" or circuit opening 90 button, by pressure of tension spring 20 which is attached to switch 42 at 65 and to spring yoke 43 by sliding catch 66 in groove 67. (Fig. 18.) Pressure on thumb latch 8 by reason of shaft 6 causes cam 60 to bear on stop 63 and the tension of spring 20 is overcome, arm 66^a presses button 62 to circuit closing position and the flow of current to the flat iron is completed. If pressure on thumb latch 8 is removed spring 20 draws 95 arm 66^b against button 61 to close the switch 42 in plug 15^a.

If left handed use is desired, thumb latch 8 is turned to the left side of the handle. (See Fig. 21.) Cam 60 is thus brought into 105 contact with stop 63^a and catch 66 is slid in groove 67 (Fig. 15) to the left of the spring yoke 43. The operation is then as explained for right hand use.

The advantages of my invention are as 110 follows: The heat supply is cut off from the flat iron when the operator takes his or her hand from the flat iron, thus fires are avoided in leaving the flat iron with the heat supply operative through carelessness 115 or haste. Furthermore, preheating can be accomplished in my improved flat iron only with my improved stand. This necessitates preheating the flat iron upon the stand—it cannot be left upon the ironing board. If 120 the iron is allowed to overheat fires are avoided.

A further advantage of my invention is that it is readily adaptable for right or left 125 handed use.

My improvement can be used with fuel supplies of different kinds. I have illustrated its use with an electrical source of fuel supply but I am aware and wish to cover by my Letters Patent the invention 130

set out in this specification and the accompanying drawings regardless of the kind of fuel used.

What I claim and desire to secure by Letters Patent is:

1. In an electric iron, a make and break switch electrically connected to the heating means and source of electrical supply, means to hold said switch normally in circuit opening position, means to change said switch to circuit closing position comprising a thumb lever, and operating means connecting said thumb lever and switch adapted to close said circuit by pressure upon said thumb lever.
2. In an electric iron, a make and break switch, electrically connected to the heating means and source of electrical supply, means to hold said switch normally in circuit opening position, means to change said switch to circuit closing position comprising a thumb lever mounted upon the handle of the said iron, and operating means connecting said thumb lever and switch adapted to close said circuit by pressure upon said thumb lever, said thumb lever and operating means being movable so as to adapt them for right or left handed operation.
3. In a circuit controlling device, an electrical switch, means to hold the same normally in circuit opening position, operating

means including a shaft and thumb lever to move said switch to circuit closing position by pressure of the operator's thumb upon said thumb lever, said switch being returned to circuit opening position by the first named means when pressure upon the said thumb rest is removed, operating means being movable so as to adapt them for right or left handed use.

4. In an electric iron, a make and break switch electrically connected to the heating means and source of electrical supply, means to hold said switch normally in circuit opening position, means to change said switch to circuit closing position comprising a thumb lever mounted upon the handle of the said iron, and operating means connecting said thumb lever, a stand adapted to receive said iron and a rod upon said stand to receive said arm and hold said switch in circuit closing position for the purpose of preheating the said iron.

Dated June 18th, 1921.
